UNITED STATES PATENT OFFICE.

HENRY C. MONTAGUE, OF WASHINGTON, DISTRICT OF COLUMBIA.

SHOE-TREE.

Application filed March 7, 1927. Serial No. 173,567.

This invention relates to shoe trees such as are used as forms on which to place shoes or slippers when not in use, to preserve their original contour and maintain their pleasing appearance.

It is an object of the invention to provide a pair of shoe trees each having a toe portion for engaging the toe of one shoe of a pair and a heel portion adapted to engage the heel of the mate shoe of the pair.

It is a further object of the invention to provide a pair of shoe trees which may be simultaneously and equally adjusted to various sizes.

Still another object of the invention is to provide a pair of adjustable shoe trees which may be suspended from a support rod or removed without disturbing the adjustment.

A still further object of the invention is to provide an improved shoe tree which is adapted to be hung from a support and protected by a cover, and which will be cheap in construction and simple in operation.

Other objects will be apparent from an inspection of the accompanying drawings, in which:

Fig. 1 is a sectional view of a shoe container showing the improved shoe tree suspended therein;

Fig. 2 is a top plan view of a pair of shoe trees according to the present invention; and

Fig. 3 is a detail perspective view of the support rod.

Referring more particularly to the drawings, the shoe trees embodying the present invention comprise a pair of duplicate members 10 and 11 which may be formed entirely of strap material and provided with toe members 12 formed of wood or other suitable material and shaped to fit the interior of the toe portion of a shoe. A similar form member may be provided for the heel portion but in the preferred form shown in the drawings the heel portion is formed by the curved end of the members 10 and 11.

Each of the duplicate members 10 and 11 consists of a length of strap material having one end suitably secured to the toe portion

12. This member extends back toward the heel of the shoe, but is abruptly curved upward as at 13 about at the beginning of the opening in a shoe as shown in Fig. 1 and bent forward parallel to the bottom of the shoe as at 14. It extends in this general direction beyond the toe portion, and is bent

slightly downward in the direction of the toe portion as at 15. At its far end, however, it is bent abruptly upward for a distance about equal to the height of a shoe as at 16 and is then again bent back toward the toe portion as at 17, forming a heel portion for the shoe tree. This portion may of course be formed of solid wood, metal or composition as desired.

Each member is further provided with a longitudinal slot 18 to permit adjustment of the pair with respect to each other. A thumb screw indicated generally at 19 serves to clamp the two members together in adjusted positions.

From the foregoing description it will be apparent that one shoe of a pair may be supported by the toe portion 12 of one member and the heel portion 16 of the other member, the other shoe of the pair being supported by the remaining toe and heel portions of the two trees. Furthermore, by simply adjusting the thumb screw 19 which works in the two slots 18, the toe and heel portions of the two separate members may be moved away from each other, to adjust the pair of trees to shoes of different sizes. Also, by this arrangement, shoes supported by the device may be placed under a slight tension, which will tend to assist in reforming or preserving the shape of the shoe. At the same time the same tension is applied to the other shoe of the same pair, which is supported by the remaining toe and heel portions of the same two members.

It should be noted that the embodiment of the shoe trees described will hold the pair of shoes superposed and in reverse position. This arrangement requires a minimum storage space for the pair of shoes, as it provides a compact unit.

When a pair of shoes has been mounted on the shoe trees in the manner set forth, they may be suspended as a unit from the portion 13 of either member, by simply hanging it over a support rod 20. The rod 20 is carried by the outwardly extending flanges 21 of a strap 22, provided with vertically extending straps 23 each having an upwardly extending tongue 24 and downwardly extending tongue 25. These tongues are adapted to be received in corresponding pockets 26 and 27 respectively constructed on the inside of a suitable dust excluding bag or container. These pockets may be simply formed by a patch 28 of the same

material as the container secured to the inside of the bag by parallel seams 29 and 30. The edge of the upper pocket 26 is spaced a distance above the strap 22 equal to the length of the lower tongue 25 so that when the tongues are being inserted in the pockets the tongues 24 may be inserted in the upper pockets 26 for their full length with the upper edge of the strap 22 at the edge of the upper pocket. The clearance just mentioned will permit the lower tongues 25 to be then inserted in the lower pockets 27 so that the rod 20 is securely supported by the wall of the container. The remaining portions of the container may be of any desired construction, but that shown in Fig. 1 is of the general type of an envelope having a lower pocket 31 and an upper flap 32 the entire bag being supported in any desired manner by the upper portion 33. The support structure just described will retain the shoes centered inside of the envelope without sagging against the inner wall and at the same time this support structure may be readily removed from the bag so that the bag may be laundered.

While one embodiment of the invention has been described in detail, the invention is not to be limited to the exact construction shown, but includes such modifications and alterations as come within the scope of the appended claims.

Having thus described the invention, what is claimed as new and desired to be secured by Letters Patent is:

1. A pair of shoe trees, comprising in combination two duplicate members, each having a toe portion for engaging the toe of one shoe of a pair, and each having a heel portion adapted to engage the heel of the mate shoe of the same pair, whereby both members cooperate to support each shoe of the pair.

2. A pair of shoe trees, comprising in combination two duplicate members, each having a toe portion curved in one direction for engaging the toe of one shoe of a pair and each having a heel portion curved in the opposite direction adapted to engage the heel of the mate shoe of the same pair, whereby both members cooperate to support each shoe of the pair.

3. A pair of shoe trees, comprising in combination two duplicate members, each having a toe portion for engaging the toe of one shoe of a pair and each having a heel portion adapted to engage the heel of the mate shoe of the same pair, whereby both members cooperate to support each shoe of the pair, and an adjustable connection between the two members, whereby they may be adjusted to fit various sizes of shoes.

4. A pair of shoe trees, comprising in combination two duplicate members, each having a toe portion for engaging the toe of one shoe of a pair and each having a heel portion

adapted to engage the heel of the mate shoe of the same pair, whereby both members cooperate to support each shoe of the pair, and means for adjusting said members whereby to vary equally the distance between the toe portion of one and the heel portion of the other.

5. In combination with a support rod, a pair of shoe trees, comprising in combination two duplicate members, each having a toe portion for engaging the toe of one shoe of a pair and each having a heel portion adapted to engage the heel of the mate shoe of the same pair, whereby both members cooperate to support each shoe of the pair, whereby the pair of shoes may be removed from said rod without disturbing the adjustment.

6. An article of manufacture, comprising a member having a main body portion, an end portion curved back toward the main body portion and formed to fit the toe of a shoe, and the other end portion curved back toward the main body portion in the opposite direction and provided with a contour to fit the heel of another shoe.

7. A device for storing shoes, comprising in combination a support having pockets, a support rod, a bracket to carry said rod, tongues on said bracket engaging said pockets and a pair of shoe trees adapted to be supported by said rod, without the necessity of any hooks or supports.

8. A device for hanging shoes from a fabric support, comprising in combination, a support rod, a pair of interconnected shoe trees adapted to support a pair of shoes as a unit hung from said rod, a bracket carrying said rod, supporting pockets in said fabric and tongues on said brackets adapted to engage said pockets.

9. A device for hanging shoes, comprising in combination, a pair of shoe trees and a support rod, the toe portion of each tree cooperating with the heel portion of the other tree to support a separate shoe, and the trees being connected, whereby the toe portion of either tree may be hung over the support rod to support the pair of shoes.

10. A device for supporting shoes, comprising in combination, a frame having separate portions to fit the toe and heel of each of a pair of shoes, and arranged to hold the shoes superposed and in reverse position, whereby a minimum of storage space for the shoes is required.

11. A device for supporting a pair of shoes, comprising in combination, a member having one end shaped to fit the interior of a shoe heel, and the other end reversely curved and shaped to fit the interior of the shoe toe portion, and a second member identical with the first mentioned member and secured thereto in reversed and superposed position with both of said members lying in

- the same plane, whereby the toe end of one member and the heel end of the other respectively cooperate to support each shoe of a pair.
- 5 12. A device for supporting a pair of shoes, comprising a unit having a toe portion and a heel portion for each shoe of a pair, and a single adjusting means for adjusting both heel and toe portions simultaneously.
- 10 13. A device for supporting a pair of

shoes, comprising in combination, a pair of members each having a portion for engaging the toe of one shoe of a pair and each having another portion for engaging the heel 15 of the mate shoe of said pair, and means for securing said members together whereby the shoes of the pair are held thereby in reversed relation.

In testimony whereof I hereunto affix my 20
signature.

HENRY C. MONTAGUE.
